UNITED STATES PATENT OFFICE

2,216,211

METHOD AND APPARATUS FOR PICKLING
METAL COILSStone Nyberg, Dover, and Herman C. Cappel, New
Philadelphia, Ohio, assignors to Agnes J. Reeves
Greer, Morgantown, W. Va.

Application October 9, 1939, Serial No. 298,540

7 Claims.

(Cl. 148—8)

The invention relates to method and apparatus for pickling coils of metal, and more particularly to certain improvements upon the general type of pickling machines disclosed in Greer Patent

5 No. 2,091,921, issued August 31, 1937; Shoemaker Patent No. 2,120,843, issued June 14, 1938; and application of Agnes J. Reeves Greer for method and apparatus for pickling metal coils, Serial No. 249,484, filed January 5, 1939 and allowed July 21, 1939.

10 Machines of the general character referred to provide for the pickling, washing and treating of coils of metal supported upon mandrels which are rotated as they are progressed through the 15 pickling and washing tanks, whereby the coils are in turn rotated by the mandrels.

As disclosed in the Greer application above referred to, it has been found desirable to rotate the coils in alternate directions, as they pass through the pickling and washing baths, in order that the multiplicity of convolutions of the coils be opened up, or separated, so as to permit free access of the solutions to all portions of the coils, whereby the pickling and washing of the metal 25 are greatly facilitated.

In machines such as above referred to, although the mandrels, and the coils supported thereon, were positively rotated while they were passing through the solutions in the tanks, there 30 was no means for positively rotating the coils during the time they were being transferred from one tank to the next, and except for a slight rotation as the transfer arms pass over center the coils merely hang suspended upon the mandrels 35 throughout the transfer period.

It has been discovered that the pickling acid 40 may be more readily removed from the surface of the metal by positively rotating the coils around their axes throughout the entire transfer period, and in some cases it may be desirable to alternately rotate the coil in opposite directions as it is being transferred from one tank to another.

It is therefore an object of the present invention 45 to provide means for positively rotating the coils around their axes as they are carried in the transfer arms from one tank to the next.

Another object is to provide means for alternately rotating the coils in opposite directions during the transfer period. A further object is 50 to provide means for rotating the coils in the transfer arms in a direction so that the top of the coil moves in a direction opposite to the movement of the transfer arms.

55 A still further object is to provide a mandrel

having a gear thereon, and an arcuate rack located in the path of the gear for positively rotating the mandrel as it is carried in the transfer arms.

Still another object is to provide sections of 5 arcuate racks arranged to alternately engage opposite sides of the gear upon the mandrel so as to alternately rotate the mandrel in opposite directions as it is carried from one tank to the next in the transfer arms.

10 The above objects together with others which will be apparent from the drawings and the following description, or which may be later referred to, may be attained by constructing and operating the improved pickling machine and 15 method in the manner illustrated in the accompanying drawings, in which

Figure 1 is a sectional elevation showing the adjacent end portions of two tanks of a pickling machine, with the interposed transfer arms and 20 means associated therewith for positively rotating the mandrels, and the coils supported thereon, throughout the time that they are being transferred from one tank to the other;

Fig. 2, a plan view of the portion of the apparatus illustrated in Fig. 1;

Fig. 3, a transverse sectional view of the machine, taken as on the line 3—3, Fig. 1;

Fig. 4, a fragmentary, detached elevation of 30 a portion of one transfer arm, showing the gear on the mandrel sleeve engaging the arcuate rack;

Fig. 5, a similar view showing the gear on the mandrel shaft engaging the rack on the transfer arm;

Fig. 6, a view similar to Fig. 1, showing a modification of the invention; and

Fig. 7, a similar view showing another modification.

Similar numerals refer to similar parts throughout the several views.

The pickling machine generally may be of the same construction as disclosed in the patents and application above referred to with the additions and improvements forming the present invention, but for the purpose of illustration, adjacent end portions of the pickling tank and first washing tank, only, are shown with the improved transfer mechanism interposed between the same, although it should be understood that the same transfer mechanism is used between the first and 50 second washing tanks.

A portion of the pickling tank is indicated at 55 10 and the adjacent portion of the first washing tank is indicated at 11. Each of these tanks may be of any suitable length depending upon the 55

speed at which the coils are advanced therethrough to obtain a proper pickling of each coil in its passage through the pickling tank and a proper washing and neutralizing of the coils as they pass through the first washing tank.

Rails 12 may be mounted at or adjacent to the top of the pickling tank at points adjacent to the side walls thereof, forming a track upon which the mandrels may be rotated throughout the length of the tank.

Each mandrel may comprise a shaft 13 having a roller 14 fixed near each end thereof and adapted to travel upon the rails 12; and a sleeve 15 rotatably mounted upon the mandrel shaft between the rollers 14.

This mandrel may be of the same construction as illustrated and described in detail in said Greer application, and may be provided with the enlarged middle portion 16 having the spaced annular grooves 17 therein for adjustably mounting the flange plates 18 upon the sleeve in order to accommodate coils of different widths.

If desired, a section of tube, as shown at 19, of considerably larger diameter than the mandrel sleeve, may be located around the enlarged central portion 16 of the mandrel sleeve between the flange plates and within the open center of the coil 20, as shown in Figs. 1 and 3.

A sprocket wheel or gear 21 is fixed upon each end portion of the mandrel shaft 13, preferably beyond the rollers 14 and is adapted to travel upon a toothed track 22 associated with the side walls of the pickling tank in the manner illustrated and described in detail in said Shoemaker patent and said Greer application above referred to.

As disclosed in the above cases these toothed tracks may be fixed to any stationary portion of the machine adjacent to the pickling tanks, such as the rails 13.

The upper side of each of the sprocket wheels 21 is adapted to be engaged by an endless drive chain 23 located around sprockets 24 near each end of the tank and preferably running beneath the longitudinal chain guides 25, as disclosed in detail in said Shoemaker patent, which insure engagement of the drive chains with the sprocket wheels 21.

The drive chains 23 may be continuously driven in unison by means of the gearing indicated at 26 and the drive shaft 27, which drives the chains in the direction of the arrows shown in the drawings, the mandrel shaft 13 being thus positively driven in a forward direction by the cooperation of the chains 23, sprocket wheels 21 and toothed tracks 22.

A sprocket wheel or gear 28 is fixed upon the mandrel sleeve 15 near one end thereof and adapted to ride upon a toothed track 29 located adjacent to one of the side walls of the pickling tank for the purpose of causing the mandrel sleeve to be positively rotated as the mandrel is moved forwardly over the tank.

As described in detail in said Greer application this toothed track 29 may be operated at one or more points between the ends of the tank for the purpose of back spinning the mandrel sleeve and coil, but this construction forms no part of the present invention and is not illustrated herein.

Thus, with the coil supported upon the mandrel sleeve, it will be seen that as the mandrel is driven forwardly upon the rails 12, by means of the drive chains 23, the sprockets 21 engaging the toothed tracks 22 will cause the mandrel shaft to be positively rotated forwardly, and during the time that

the sprocket 28 upon the mandrel sleeve is in contact with the toothed track 29 the mandrel sleeve 15, and with it the coil 20, will be positively rotated in the same direction and at the same speed as the mandrel shaft 13.

Between the discharge end of the pickling tank 10 and the entrance end of the first washing tank 11 is located the transfer mechanism which includes a shaft 30 journaled in bearings 31 and provided with a spaced pair of coil transfer arms 32 each having a coil engaging hook 33 at its free end.

A motor or other driving means arranged to be automatically operated as described in the above mentioned patents, as each mandrel is received in the hooks 33 may be operatively connected to the shaft 31 through suitable gearing indicated generally at 34.

The hooks 33 of the transfer arms may be substantially the same as described in the Shoemaker patent except that the track portion of each hook including the toothed track 35 which engages the sprockets 21 of the mandrel shaft is preferably convex forming an arc of a circle drawn from the center of the shaft 30.

In the patents and application above referred to the mandrel and the coil supported thereby hang in a substantially stationary manner in the hooks of the transfer arms throughout the entire transfer operation, the only movement of the same being a rolling movement of the mandrel between the ends of the hooks as the transfer arms pass over center.

It has been found however, that the efficiency of the machine may be increased by continuing the rotation of the mandrel and coil supported thereon throughout the entire transfer period and this rotation may be either backward or forward or alternately backward and forward as the transfer arms move the coil from one tank to the next.

This rotation of the coil as it is removed from the bath and carried through the air between the tanks greatly assists in removing the liquid from the coil, when used between the pickling tank 45 and first washing tank expedites the washing of the pickling acid from the coil and prevents carrying of an excess of acid into the washing tank.

As shown in Figs. 1 to 3, inclusive, continuous backward rotation of the mandrel and coil supported thereon may be attained by means of an arcuate frame 36 located in the adjoining ends of the two tanks and provided with the substantially half-round toothed track 37 concentric with the shaft 30 and arranged to engage the sprocket wheel or gear 28 upon the mandrel sleeve 15 when the transfer arms 32 are swung through the path of their movement.

With this construction as the transfer arms are swung from the full line position to the dotted line position shown in Fig. 1, the sprocket or gear 28 will engage the toothed track 37 rotating the mandrel sleeve backward so that the top of the coil will be moving toward the left while the coil moves bodily to the right, as viewed in Fig. 7. This rotation of the coil as it hangs suspended upon the transfer arms causes substantially all of the pickling fluid to be drained therefrom.

The first washing tank 11 is preferably of greater depth than the acid or pickling tank as best shown in Fig. 1 so that the entire coil may be submerged in the water as it is passed through the tank. For this reason the first washing tank 75

11 may also be of greater width than the pickling tank so as to receive the entire length of each mandrel therein as shown in Fig. 2.

Rails 38 may be supported inside of the tank 11, extending along the side walls thereof and preferably at a point considerably below the top of the tank as shown in Fig. 1 to receive the flanged rollers 14 upon the mandrel shaft in such position that the entire coils may be entirely submerged within the washing and neutralizing solution when the coils are received in the tank 11 as shown in Fig. 1.

A pair of driving chains 39, similar to the chains 23, may be provided for engagement with the sprockets 21 upon the mandrel shaft for moving the mandrel with the coils supported thereon forwardly through the tank 11, the sprockets 21 upon the mandrel shaft are adapted to ride upon the toothed tracks 40 associated with the rails 38 in the first washing tank, and a toothed track 41 similar to the track 29 is located in the washing tank, for engagement with the sprocket wheel or gear 28 upon the mandrel sleeve.

Curved guides 42 may be provided at the charging end of the tank 11 for receiving the ends of each mandrel to guide the mandrel into position upon the rails 38 and beneath the drive chains 39.

Although the improved transfer mechanism for rotating the coils during the transfer period is illustrated only as located between the pickling tank and the first washing tank it is to be understood that similar transfer mechanism may be mounted between the first and second washing tanks also, the construction and operation of such transfer mechanism being the same as illustrated in the accompanying drawings and above described.

The transfer mechanism may be modified as shown in Fig. 6, so that the coil may be alternately rotated in opposite directions during the transfer period.

For this purpose the machine may include alternate sections of arcuate toothed tracks 43 and 44 for engaging the under side and upper side respectively of the sprocket wheel or gear 28.

In Fig. 7 is shown a further modification in which the coil may be continuously rotated forwardly throughout the entire transfer period by means of an arcuate toothed track 44 adapted to engage the under side of the sprocket wheel or gear 28.

According to the provisions of the patent statutes, we have explained the principle of our invention and described further embodiments thereof, but we desire to have it understood that within the scope of the appended claims the invention may be practiced otherwise than as specifically illustrated and described, the invention residing in the positive rotation of the coils upon the mandrels as they are being transferred from one tank to another regardless of the mechanism by which this rotation may be accomplished.

We claim:

1. The method of pickling, washing or treating a coil of metal supported upon a mandrel which includes transferring the coil from one

bath to another bath and rotating the coil around its axis throughout the entire time it is being transferred from one bath to the other.

2. The method of pickling, washing or treating a coil of metal supported upon a mandrel which includes transferring the coil from one bath to another bath and rotating the coil around its axis so that the direction of rotation at the top of the coil is in a direction opposite to the direction in which the coil is moving, throughout the entire time it is being transferred from one bath to the other.

3. The method of pickling, washing or treating a coil of metal supported upon a mandrel which includes transferring the coil from one bath to another bath and rotating the coil around its axis alternately in opposite directions throughout the entire time it is being transferred from one bath to the other.

4. Apparatus for pickling, washing or treating a coil of metal, including two adjacent tanks containing liquid, a mandrel upon which the coil is supported, transfer arms between the tanks, each arm having a hook at its ends for receiving the mandrel, means for moving the transfer arms between the tanks for transferring the coil from one tank to the other, and means in the path of the mandrel for rotating the mandrel and the coil supported thereon throughout the entire time of said transfer.

5. Apparatus for pickling, washing or treating a coil of metal, including two adjacent tanks containing liquid, a mandrel upon which the coil is supported, said mandrel comprising a shaft and a sleeve rotatably mounted upon the shaft, a gear on the sleeve, means for transferring the mandrel with the coil thereon from one tank to the other, and a rack in the path of the gear for rotating the sleeve so that the direction of rotation at the top of the coil is in a direction opposite to the direction in which the coil is moving throughout the entire time of said transfer.

6. Apparatus for pickling, washing or treating a coil of metal, including two adjacent tanks containing liquid, a mandrel upon which the coil is supported, transfer arms between the tanks, each arm having a hook at its ends for receiving the mandrel, means for moving the transfer arms between the tanks for transferring the coil from one tank to the other, and means in the path of the mandrel for rotating the mandrel and the coil supported thereon alternately in opposite directions throughout the entire time of said transfer.

7. Apparatus for pickling, washing or treating a coil of metal, including two adjacent tanks containing liquid, a mandrel upon which the coil is supported, said mandrel comprising a shaft and a sleeve rotatably mounted upon the shaft, a gear on the sleeve, means for transferring the mandrel with the coil thereon from one tank to the other, and racks in the path of the gear for successively engaging the top and bottom of the gear for rotating the sleeve alternately in opposite directions throughout the entire time of said transfer.

HERMAN C. CAPPEL.
STONE NYBERG.
